UNITED STATES PATENT OFFICE.

CHARLES DUCAS, OF NEW YORK, N. Y.

FIRE-BOX FOR BOILERS.

1,353,640.

Specification of Letters Patent. Patented Sept. 21, 1920.

Application filed July 10, 1917. Serial No. 179,639.

To all whom it may concern:

Be it known that I, CHARLES DUCAS, a citizen of the United States, residing in New York city, in the county of New York and State of New York, have invented certain new and useful Improvements in Fire-Boxes for Boilers, of which the following is a specification.

This invention relates to improvements in sectional stayed fire boxes, the primary object of which is to provide a fire-box construction in which stay bolts have a universal connection with the outer or wrapper sheet of the fire-box and also a universal connection with the inner or crown sheet thereof whereby all unequal or excessive strains due to expansion or contraction of the parts or such other strains to which the ordinary fire-box is subjected are prevented.

Another object of the present improvement is to devise a stay bolt so constructed that each end thereof is universally movable mounted within supports which are carried by the inner and outer walls of the fire-box.

Another object of this invention is to provide a fire-box construction in which both the wrapper and crown sheets thereof are sectional, stay bolts being connected to the joints of one shell and between the joints of the other shell.

A still further object of the present improvement is to construct a fire-box using a crown sheet composed of U-shaped sections and slotting the vertical edges of the U-shaped sections, or otherwise removing a portion of the metal therefrom, whereby the inequality of expansion and contraction of the horizontal walls relative to that of the vertical legs of the sheet is compensated, the inequality of expansion being due to the difference in the proximity of the horizontal walls and vertical legs of the crown sheet to the fire. This equalizing and compensating action will augment the universality of the relation between a crown sheet and wrapper sheet which are connected by universally movable stay bolts.

A still further object of the present improvement is to provide a fire-box construction in which the flue sheet, back head and door plate are butt welded to the mud ring, wrapper and crown sheets permitting the boiler to be made much cheaper than those having flanges and rivets are employed, thus

Other and further objects of the present improvement will be set forth in detail in the following description and drawings in which

Fig. 1 is a fragmentary vertical sectional view through one of the flexible stay bolts and showing its connection to the wrapper and crown sheets of the fire-box.

Fig. 2 is a vertical sectional view similar to Fig. 1 and taken at right angles thereto.

Fig. 3 is a top plan view of the brackets which are applied to the joints of a sectional sheet for receiving one end of a stay bolt.

Fig. 4 is a view similar to Fig. 1 except showing the stay bolt applied to a sectional crown sheet between the joints of which a stay sheet is interposed.

Fig. 5 is a fragmentary vertical section through a fire-box in which both the crown sheet and wrapper sheet are sectional and showing the attachment of the stay bolts thereto.

Fig. 6 is an end elevation of a fire-box construction provided with my improvements showing the same partly broken away to show the flue sheet.

Fig. 7 is an enlarged fragmentary perspective view of one section of the crown sheet showing the same slotted to compensate for the relative difference in the expansion and contraction of the horizontal and vertical walls thereof.

Fig. 8 is a vertical sectional view through a fire-box constructed in accordance with my improvements and showing in detail the welding of the flue sheet, door sheet and back head to the mud ring, crown sheet and wrapper sheet.

Fig. 9 is a fragmentary perspective view illustrating the usual method of connecting the door plate and crown sheet.

Fig. 10 is a fragmentary perspective view illustrating the improved method of attaching the door plate to the crown sheet by butt welding.

All of the improvements hereinafter to be described in detail pertain to fire-boxes of the Jacobs and Shupert type as illustrated in Patents Numbers 917,172; 982,723, and 1,054,420, which may be taken as examples.

The constructions illustrated in these patents comprise essentially a fire-box having a wrapper and crown sheet with stay bolts between them, the stay bolts being mounted so

- and the side walls of the crown-sheet members being provided with vertical slots to permit of expansion and contraction, and prevent distortion of such members by reason of the unequal heating of the central and side walls of such section members, the universal connections having their universal movable joint socket-portions located in slots formed in the abutting side walls.
- 10 5. A steam-boiler fire-box construction, comprising a wrapper-sheet; a sectional crown-sheet; stay-bolt members movably connected at one end with the wrapper-sheet by a ball and socket universal-joint, and at the other end with the sectional crown-sheet; the sections of the crown-sheet being of substantially U-shape in cross-section and having the side walls thereof secured together; and the side walls of the crown-sheet members being provided with vertical slots to permit of expansion and contraction and prevent distortion of such member by reason of the unequal heating of the central and side walls of such section members, the universal connections connecting the stay-bolt members with the sectional crown-sheet members by their socket portions located in slots formed in the abutting side walls of the sectional crown-sheet members.
- 15 6. A boiler fire-box construction comprising a wrapper-sheet; a crown-sheet composed of a plurality of sections having upstanding abutting side-flanges by which each of the sections is secured to the adjacent abutting sections; ball-joint spheriodally cavitated supporting journal members secured to the wrapper sheet; bracket or side-securing yoke-pieces secured to opposite sides of the upstanding flanges of the crown-sheet sections securing them together; a spherically hollow ball-joint journal piece or seat member located within each pair of brackets and secured therein; and stay-bolt members securing the crown-sheet and the wrapper-sheet together, having a ball at either end fitting within the spherical-supports of the crown-sheet and in the said securing-yoke bracket-members, whereby the wrapper-sheet and crown-sheet are secured and stayed together upon universal movably jointed bolts.
- 20 7. In a steam-boiler fire-box construction, a wrapper-sheet; a ball-socket spherically cavitated stay-bolt securing journal member secured in such wrapper-sheet; a stay-bolt provided with a spheroidal ball at one end forming with the securing journal, a universal ball-joint; a crown-sheet composed of a plurality of substantially U-shaped members, the upstanding flanges of which are secured together and transversely securing bracket pieces or side-yokes having between them formed thereby a central cylindrical cavity provided with a female screw-thread, such side-yokes being bolted to

gether upon the flanges of the U-shaped sections of the crown-sheet; and a universal ball-socket journal piece adapted to be screwed down into the cavity of the two-yoke members upon a ball on the inner end 70 of a stay-bolt, which is secured, by a like ball at the other end in the securing journal, carried by the wrapper-sheet.

8. In a steam-boiler fire-box construction, a wrapper-sheet; a ball-socket spherically 75 cavitated stay-bolt journal-member secured in such wrapper-sheet; a stay-bolt provided with a spheroidal ball at one end located in the journal, so as to form a universal ball-joint; a crown-sheet composed of a plurality of substantially U-shaped members, the upstanding flanges of which are secured together, having transverse slots; securing bracket pieces or side-yokes having a central spherical cavity provided with a female screw-thread bolted together upon the flanges of the U-shaped sections of the crown-sheet; and a universal ball-socket journal-piece adapted to be screwed down into the cavity of the two yoke-members 85 upon a ball formed upon the inner end of a stay-bolt.

9. In a steam-boiler fire-box construction, a wrapper-sheet; a ball-socket spherically 95 cavitated stay-bolt journal-member secured in such wrapper-sheet; a stay-bolt provided with a spheroidal ball at one end located in the journal, so as to form a universal ball-joint; a crown-sheet composed of a plurality of substantially U-shaped members, the 100 upstanding flanges of which are secured together, having transverse slots; securing bracket pieces or side-yokes having a central spherical cavity provided with a female screw-thread bolted together upon the flanges of the U-shaped sections of the crown-sheet; and a universal ball-socket journal-piece adapted to be screwed down into the cavity of the two yoke-members 105 upon a ball formed upon the inner end of a stay-bolt, the ball being provided with an undercut central slot; and a securing pin 110 passing transversely through the two yoke-pieces lying in such undercut slot.

10. A steam-boiler fire-box construction, 115 comprising a wrapper-sheet; a crown-sheet composed of longitudinal substantially U-shaped sections; spherical cavitated-ball journals carried by the wrapper-sheet; brackets or securing side yoke-pieces adapted to be secured to the side walls or flanges of the crown-sheet sections so as to secure the same together when arranged on opposite sides of such side walls, so as to cover slots formed therein, so as to form by the 120 coaction of such side yoke-pieces or brackets a cylindrical screw threaded sleeve; stay-members having a ball or cylindrical universal-joint portion at either end, the outer 125 one of which is supported in a spherical 130

- support of the wrapper-sheet, and the lower like spherical ball of which is located in the screw-threaded central sleeve-portion formed between the two brackets, and is held in 5 place by a male threaded hollow ball-receiving spheroidally cavited journal-sleeve.
11. A steam-boiler fire-box construction comprising a wrapper-sheet; a crown-sheet composed of longitudinal substantially U-shaped sections; spherically cavited ball-journal-supports carried by the wrapper-sheet; brackets or securing side yoke-pieces adapted to be secured to the side walls or flanges of the crown-sheet sections so as to 10 secure the same together when arranged on opposite sides of such side walls or flanges, so as to cover slots formed therein, so as to form by the coaction of such side-yoke-pieces or brackets, a cylindrical screw-threaded sleeve; stay-members having a spheroidal universal-joint portion at either end, the outer one of which is supported in a spherical cavited journal support of the wrapper-sheet, and having the lower like 15 spherical ball located in the screw-threaded central sleeve portion formed between the side-yoke pieces or brackets, which lower ball is held in place by a male threaded hollow ball-receiving spheroidally cavited journal-sleeve, the lower ball so held in place being provided with a central undercut groove to receive a securing rivet-bolt lying in such slot passing through the side-yokes or bracket pieces.
- 35 12. A fire-box construction comprising a wrapper-sheet; a crown-sheet composed of a plurality of sections having upstanding flanges at their abutting joints; spherically cavited ball-journal supports carried by the 20 wrapper-sheet; securing side yoke-pieces or brackets comprising ears carrying a half sleeve between them, said bracket or side yoke pieces being arranged on opposite sides of the upstanding flanges of the abutting 25 crown-sheet sections, so that the semi-circular parts of the split-sleeves thereof together form a cylindrical chamber, the ears or end pieces of the side-yokes or brackets being attached to the upstanding flanges; and 30 stay members having a spherical portion at either end fitting within the said cylindrical chamber at one end and the cavited ball-journal supports of the wrapper sheet at the other; whereby the wrapper-sheet and 35 crown-sheet are universally movably mounted in relation to each other, for movable temperature expansive and contractive adjustment without strain.
13. A fire-box construction comprising a 40 wrapper-sheet; a crown-sheet composed of a plurality of sections having upstanding flanges at their abutting joints; spherically cavited ball-journal supports carried by the wrapper-sheet; side-yoke or bracket pieces 45 having a central semi-cylindrical sleeve por-
- tion, attached to opposite sides of the upstanding flanges whereby they together form a sleeve provided with an internal screw thread; a bushing having external screw threads; sleeves having a hollow cavited 50 spherical-portion located in the split-sleeve thus formed and stay-members or bolts having a spherical portion at either end, one end fitting within the spherical supports carried by the wrapper-sheet, and the other end held within the sleeves by the spherical cavited portion of the male threaded bushing.
14. A fire-box construction comprising a 55 wrapper-sheet composed of a plurality of sections having connecting side-securing flanges arranged at a right angle to the main central portion; a crown-sheet composed of a plurality of sections similar to the wrapper-sheet sections having the securing flanges of the crown-sheet and wrapper-sheet arranged parallel but staggered; spherical cavited supports carried by the wrapper-sheet between the flanges; spherically cavited supports carried by the flanges 60 of the crown-sheet; and stay-members in the form of bolts each having a spherical portion at either end fitting within the said supports; whereby the wrapper-sheet and crown-sheet are universally movably mounted 65 in relation to each other.
15. A fire-box construction comprising a 70 wrapper-sheet; and a crown-sheet composed of a plurality of sections having upstanding securing side flanges; the said flanges having portions of metal removed therefrom at a plurality of points at the outer portion, and stay bolt journal securing members mounted in the recesses formed by said removed portions for the reception of stay- 75 bolt journal securing members.
16. A fire-box construction comprising a 80 wrapper-sheet; and a crown-sheet composed of a plurality of sections having upstanding securing side flanges; the said flanges having portions of metal removed therefrom at a plurality of points at the outer portion whereby the flanges have a different height at a plurality of points, and stay bolt journal securing members mounted in the recesses formed by said removed portions.
17. A fire-box construction comprising a 85 wrapper-sheet, and a crown-sheet composed of a plurality of substantially flat-bottomed U shaped sections, the vertical legs of the 90 U shaped sections being provided with a plurality of slots made in the upper edges thereof, whereby the said vertical legs have a different height at a plurality of points, and stay bolt journal securing members 95 mounted in the recesses formed by said removed portions.
18. A boiler fire-box construction comprising a wrapper-sheet; a sectional crown-sheet composed of a plurality of substan- 100

tially U shaped sections; the adjacent abutting securing flanges of such sections having a stay sheet interposed between them; securing rivets passing through such side flanges and interposed stay-sheet; side-yoke or bracket-members attached to the members of the crown-sheet section; and stay-bolts or members connected by a universal joint at one end to the flanges of the crown-sheet; and at the other end in a like manner to the wrapper-sheet.

19. A boiler-fire-box construction comprising a sectional crown-sheet composed of a plurality of substantially U-shaped sections, the adjacent abutting securing flanges or side walls of which abutting sections have a stay-sheet interposed between; a sectional crown-sheet formed of like shaped sections; securing rivets passing through such side flanges and interposed stay-sheet of the sectional wrapper-sheet and sectional crown-sheet; side-yoke or bracket-members attached to the flanges of the crown-sheet sections; and stay-bolts or members connected by a universal joint at one end to each of the side yokes of the bracket members attached to the crown-sheet section flanges; and attached at the other end in a like manner by universal-joints to the wrapper-sheet.

20. A boiler fire-box construction comprised of a plurality of substantially flat bottomed U shaped sections, which when secured together at the flanged or leg portions, constitute a sectionally formed crown-sheet and side-wall member of the fire-box; the substantially horizontal crown-sheet portion, and the side-wall portion being each provided with expansion slots in the flanges; and with universal-joint cavitated bracket-pieces secured thereto forming ball-journal sockets; in each of which is universally mounted the ball of stay-bolt extending outward from the crown-sheet or the side furnace-wall, and secured to the wrapper-sheet by a like universal stay-bolt joint.

21. In combination, a wrapper-sheet comprising channel members having inwardly turned flanges abutting the flanges of the adjacent sections; a crown-sheet comprising channel sections having outwardly turned side flanges abutting the flanges of the adjacent crown-sheet sections and staggered with the flanges of the wrapper-sheet sections; and stay bolts having universal connection with said outturned flanges and the intra-marginal portion of the wrapper sheet sections.

22. In combination, wrapper-sheet sections comprising channel members having inwardly turned flanges abutting the flanges of the adjacent sections; a crown-sheet; and stay bolts having connection with said crown-sheet and the intra-marginal portion 65 of the wrapper sheet sections.

23. In combination, a wrapper sheet; crown-sheet sections having outturned flanges secured to the flanges of the adjacent sections, and provided with registering cut out portions at the edges, and with slcts 70 extending to near the yoke portion of the section and communicating with said cut-out portion; and stay bolts having connection with said outturned flanges and the wrapper sheet.

75
24. In combination, a wrapper sheet; a crown-sheet comprising sections having outturned flanges secured to the flanges of the adjacent sections, and provided with registering transverse slots extending to near the yoke portion of the section; and stay bolts having connection with said outturned flanges and the wrapper-sheet.

25. A crown-sheet comprising sections having outturned flanges secured to the flanges of the adjacent sections, and provided with transverse registering slots 85 extending to near the yoke portion of the section.

26. In combination, a wrapper-sheet; 90 crown-sheet channel sections having outwardly turned side flanges secured to the flanges of the adjacent crown-sheet sections and provided with registering rectangular cut-out portions at the edges; a socket seated 95 in each cut-out portion; and stay bolts having universal connection with said wrapper, sheet and said sockets.

27. In combination, a wrapper-sheet; 100 crown-sheet channel sections having side flanges abutting the flanges of the adjacent sections and provided with registering cut-out portions; a socket seated in each cut-out portion; and stay bolts having connection with said wrapper-sheet and said sockets. 105

28. In combination, spaced sheets, one of which comprises channel sections having side flanges abutting the flanges of the adjacent sections and provided with registering rectangular cut-out portions; and stay bolts having connection with said sheets and one end seated in said cut out portion.

29. In combination, spaced sheets, one of which comprises channel sections having side flanges provided with cut out portions; 115 and stay bolts having connection with said sheets and one end in said cut out portion.

30. In combination, a wrapper sheet; 120 crown - sheet sections having outturned flanges secured to the flanges of the adjacent sections, and provided with registering cut out portions at the edges; a pair of bracket members secured at their opposite ends to the side face of adjacent flanges at said cut-away portions and provided with opposed 125 cavities together forming a threaded sleeve; a threaded bushing in said sleeve and cut-away portion and provided with a spherical interior socket surface; a transverse pin diametrical to the lower part of said sleeve 130

and holding the bracket members from spreading apart; and a plurality of stay bolts, each having a universal connection at its outer end with the wrapper sheet and a substantially spherical inner end received by said socket surface and provided with a transverse end groove receiving said pin.

31. In combination, a pair of sheets one of which comprises sections having flanges secured to the flanges of the adjacent sections, and provided with registering cut-out portions at the edges; bracket members secured to the flanges at said cut-away portions and together forming a sleeve; a bushing in said sleeve and cut-away portion and provided with a socket; and a plurality of stay bolts, each having universal connection with one sheet and a substantially spherical end received by said socket.
32. In combination, wrapper-sheet sections comprising channel members having intra-marginal threaded openings and inwardly turned flanges abutting and secured to the flanges of the adjacent sections; a crown-sheet; a plurality of stay bolts connected to the crown-sheet and each having a threaded outer end; socket sleeves having spherical sockets in their outer ends and having reduced ends received in said intra-marginal openings; ball shaped nuts received on the outer ends of said stay bolts and seated in said sockets; and interiorly threaded caps

mounted on the outer ends of said socket sleeves and covering said nuts.

33. In combination, wrapper-sheet sections comprising channel members having intra-marginal openings and inwardly turned flanges secured to the flanges of the adjacent sections; a crown-sheet; a plurality of stay bolts connected to the crown-sheet and each having a threaded outer end; socket sleeves having spherical sockets in their outer ends and having reduced ends received in said intra-marginal openings respectively; and ball-shaped nuts received on the outer ends of said stay bolts and seated in said sockets.

34. In combination, a wrapper-sheet comprising sections having inturned flanges secured to the flanges of the adjacent sections; crown-sheet channel sections having outwardly turned side flanges abutting the flanges of the adjacent crown-sheet sections; stay bolts having universal connection with said outturned flanges and the intra-marginal portion of the wrapper-sheet sections; and rivets passing through adjacent flanges of the crown-sheet sections between the universal connection and the body portion of the section and holding the flanges in steam-tight contact throughout.
